UNITED STATES PATENT OFFICE.

JOHN W. FERREE, OF PHOENIX, ARIZONA.

BURNER.

1,369,230.

Specification of Letters Patent. Patented Feb. 22, 1921.

Application filed March 20, 1920. Serial No. 367,555.

To all whom it may concern:

Be it known that I, JOHN W. FERREE, a citizen of the United States, residing at Phoenix, in the county of Maricopa and State of Arizona, have invented certain new and useful Improvements in Burners, of which the following is a specification, reference being had to the accompanying drawings.

10 This invention relates to an improved burner and preferably to the type with which coal oil as a fuel is used.

Many burners of this kind have been found more or less of very little real value owing to their expensive complicated construction, therefore, the invention aims to provide an improved coal oil burner which is very simple, efficient and practical in construction and capable of being cheaply made 20 and sold at a reasonable profit.

As a further object it is the aim to provide a coal oil burner which is not expensive to install and operate, and furthermore, will operate with a minimum amount of fuel. In 25 other words, a very small amount of fuel is allowed to enter the gas chamber together with air to mix with the oil vapor and at the same time will generate a great amount of heat.

30 The invention still further aims to provide a burner of this kind wherein an elongated tubular generator is employed, supporting the burners as shown, there being a gas chamber in communicative connection 35 with the generator, in combination with an air supply pipe communicating with the gas chamber at a point where the chamber and the generator connect so that a mixture of air and gas is allowed to enter the gas chamber and thence into the burner where the mixture may be ignited.

The invention also embodies the use of a saturated asbestos member held in a position beneath the generator in order to initially 45 heat the generator for the purpose of vaporizing the coal oil or other fuel, which is supplied to the generator and as the mixture of vapor and air constitutes a suitable burning gas, it enters the burners and escapes 50 through the slots thereof, where it becomes ignited. In order to ignite the escaping gas from the slots of the burners, a suitable asbestos member mounted on a handle is first 55 saturated with alcohol or gasolene and is then lighted and held under the generator until the oil is properly vaporized. If the

oil is vaporized and is mixed with the air, the charge is capable of being ignited as it leaves the burners by placing the lighted asbestos over the slots. As the burners are 60 either to the side or under the generator, the heat from the burners ascends and keeps the generator highly heated so as to always vaporize the oil as it enters the generator.

Additionally the invention embodies slot- 65 ted burners which consist of burner chamber provided with laterally extending tubes which are slotted to permit of the escape of the burning gas in order that it may be ignited as it passes off from the burner. It 70 is also the aim to provide a shut off cock in the gas chamber so as to shut off one burner when only one is needed.

While the design and construction at present illustrated and set forth is deemed preferable, it is obvious that as a result of a reduction of the invention to a more practical form for commercial purposes, the invention may be susceptible to changes, and the right to these changes is claimed, pro- 75 vided they are comprehended within the scope of what is claimed.

The invention comprises further features and combination of parts, as will be herein-after set forth, shown in the drawings and 80 claimed.

In the drawings:—

Figure 1 is a perspective view of the improved burner constructed in accordance with the invention, and showing the same 90 mounted upon supporting legs, in combination with a skeleton plate or frame over the burners for the support of cooking vessels and the like,

Fig. 2 is a longitudinal sectional view on line 2—2 of Fig. 1,

Fig. 3 is a sectional plan view on line 3—3 of Fig. 2,

Fig. 4 is a transverse sectional view on line 4—4 of Fig. 3,

Fig. 5 is a plan view of the burner showing the same provided with an extension so as to disclose that additional extensions may be employed whereby a plurality of slotted burners may be afforded.

Fig. 6 is a side view of Fig. 5, and

Fig. 7 is a detail view of the lighter implement.

Referring more especially to the drawings, 1 designates an elongated pipe or tube at 110 one end of which is provided with a coupling 2 whereby a supply pipe 3^g of a fuel tank

may be connected in order to supply any suitable fuel, preferably coal oil to the tube or pipe 1. The interior of this tube or pipe 1 is provided with a plurality of wire fabric disks 2^a arranged at intervals, and intermediate asbestos fillers 3^a through which the oil percolates and as the oil percolates through this filler of asbestos, the carbon is eliminated. This tube or pipe 1 with its 10 interior filler constitutes a generator which becomes highly heated so that the oil, when it percolates through the generator, becomes vaporized in order to thoroughly mix with the air in the mixing gas chamber. The end 15 of the tube or pipe 1 opposite its coupling 2 is provided with a cap 3 having a very small orifice or needle opening 4 to permit of the escape of the vapor which is generated from the oil in the generator. This 20 vapor as it is generated enters the gas mixing chamber where it mixes with the air which is drawn thereinto. The end portion 25 of the tubular generator having the cap 3 passes through a cap 5 which is connected to the end portion of the semi-circular part 6 of the burner. This semi-circular part 6 has an air and gas mixing chamber 6^a and connected to this semi-circular part 6 is a valve 6^b which may be open to permit air 30 to enter the mixing chamber to mix with the gas and vapor. This semi-circular part is coupled by means of the union 6^c to the pipe or tube 7, which has a gas chamber 7^a; into which the mixture of gas and air enters. 35 The gas chamber 7^a is elongated and may be any suitable length. A tubular brace 11 is provided and has one end coupled by means of a union 11^a to a curved semi-circular part 6 of the device. The other end 40 of the tubular brace is coupled by means of the union 11^c to a semi-circular tubular section or brace 11^d which in turn is coupled by means of union 11^e to the gas chamber tube or pipe 7. The union 11^e is in the form 45 of a sleeve or coupling with a centrally located division wall, acting to close the end of the gas chamber pipe or tube 7. In fact, there is no communicative connection between the gas chamber tube or pipe 7 and the interior of the brace parts 11 and 11^d. The 50 connection 10 of the curved tubular brace portion 11^b with the semi-circular part 6 of the device is also a closed connection. Supported by the pipe or tube 1 and arranged 55 to either side thereof or under the same are burner bodies 14 having burner chambers 15. These burner bodies as shown are not in communication with the generator tube 1, that is to say, where the burner bodies pass 60 under the generator tube. The burner bodies are supported and braced by connection with the tubular brace 11 as at 17. The burner bodies 14 have laterally projecting burners proper 18, and these burners proper 18 are 65 arranged in parallel planes and are provided

with slots 19 to permit the escape of the mixture of air and vapor, which constitutes a burning gas to be lighted. The burner bodies 14 are communicatively connected as at 14^a with the burner chamber 7^a of the pipe 70 or tube 7 so that the mixture of air and vapor may enter the burner bodies and then escape from the slots of the burners proper. It is to be noted that the gas chamber tube 7 at a point between the burner bodies is 75 provided with a shut off cock 20 by means of which the burning gas can be shut off from one set of burners when only one set of burners is needed.

Projecting laterally outwardly and downwardly from the tube or pipe 7 are suitable supporting legs 21. Also projecting laterally and downwardly from the brace tube 11 are supporting legs 22, which coöperate with the legs 21 in order to support the entire 85 burner structure on a table or other suitable support.

A skeleton frame or what may be termed a hot plate 23 is provided. This skeleton frame comprises the outer marginal portion 90 24 and the circular vessel supporting inner parts 25, which have inwardly extending web portions 26. The inner circular parts 25 of the skeleton frame are connected to the outer marginal portion of the frame by 95 means of the web members 27. This skeleton frame may be supported in any suitable manner over the burner apparatus, as for instance by means of the supports 28, which may be either integral or detachably connected to the brace tube 11 and the tube 7. As this is a minor detail as to how the supports 28 are connected, it is immaterial whether they are shown as being integral or detachably connected to the tube or pipe 100 7 on the brace tube or pipe 11. It is to be noted that while this vessel supporting skeleton frame or hot plate is shown and described, it is to be understood that it does not constitute an essential part of the present invention, with the exception that it provides a means for supporting the vessel over the burner proper, and if necessary the plate or frame may be so claimed, that is to say generically in order that any form of frame 110 115 can be used. It is also immaterial whether the burners proper extend laterally from the generator pipe or tube or under the same, as this is an immaterial unessential detail. However, better results have been obtained 120 by disposing the burner proper under the generator tube or pipe 1 in order that the heat from the burner proper may impart heat to the generator for the purpose of pre-heating the oil and thereby vaporizing the 125 same.

As shown in Figs. 5 and 6, the burner apparatus is illustrated as being extended by utilizing an extension burner. In order to accomplish this it is to be noted that the 130

unions 11^c and 11^e are detached and in their stead a burner extension 28^a is substituted. This burner extension 28^a is connected to the tube or pipe 7 by the union 29. This burner extension also includes an extension generator tube 31 which also assists in supporting additional burners 32 proper. This extension generator tube is coupled to the generator tube 1 by the union 33. The extension burner includes an extension brace tube 34 which in turn is coupled by means of the union 35 to the brace tube 11. The extension brace tube and the extension tube (which is connected to the tube or pipe 7) have additional legs 36 to further support the apparatus. After applying the extension burner to the tube 11 and pipe or tube 7, the substantially semi-circular portion 11^d is then connected to the extension brace tube and the extension tube of the tube 7 by means of the unions 11^c and 11^e. The extension burner also carries an extension skeleton frame 37 in a similar manner as the first skeleton frame. This extension frame has the ends of its side pieces coupled as at 38 to the first skeleton frame so that the entire structure has rigidity. It will be noted that by the construction herein disclosed, a burner construction of considerable length 30 may be devised, so that quite a number of cooking vessels may be supported over the burner proper, so that quite a number of articles may be cooked upon the device at one time.

As shown in Fig. 7 a handle member 39 is provided having an asbestos body 40 on one end which may be saturated with alcohol or gasoline and held under the generator tube thereby acting to impart heat to the generator tube 1 so as to vaporize the oil as it percolates through the web and asbestos filler and then when the proper mixture of gas escapes from the slots of the burners proper, the lighted asbestos body of the handle may be held over the burner proper in order to ignite the gas. The flame from the saturated asbestos body will rise and highly heat the generator, thereby vaporizing the oil and this vapor will pass out through the orifice or needle opening and subsequently mix with the air passing upwardly into the mixing chamber of the semi-circular part 6 of the device. The mixture will then pass on to the burner proper. The pipe including the air controlling valve to the mixing chamber acts as a flue which furnishes air to be mixed with the vapor passing from the generator into said mixing chamber. This improved burner is designed for use in country towns or cities beyond the gas district and also may be used in other places where no heavy fires are required. It is obvious that a meal can be readily cooked on the surface of the skeleton plate as well as upon the upper face of any

conventional form of cook stove and as well as on any other gas stove receiving its supply from a plant. The present device may be used as a hot plate for general cooking, the same as used with natural gas and the same has been found very much needed. When the mixture of vapor and air escapes from the slots of the burner proper and is ignited, a very hot blue flame is provided.

The semi-circular part 6 of the burner is provided with a valve controlled outlet 6^b to join the mixing chamber in case of accidental flooding of the oil when turning on the oil from the supply tank. Any suitable fuel may be used for soaking the asbestos lighting member, say for instance, alcohol or gasoline.

As previously stated herein, any suitable fuel may be used in connection with this burner and if found necessary acetylene fuel may be used as this kind of fuel may be employed to advantage for cooking purposes.

The invention having been set forth, what is claimed as new and useful is:

1. In a burner as set forth, the combination with a tubular generator having a filler of wire fabric and asbestos, of a tubular gas chamber, burners communicatively connected with the gas chamber and being supported under the generator in order to impart heat thereto for vaporizing the oil as it percolates through the filler, a mixing chamber connecting the generator and the gas chamber, an air supply for the mixing chamber, whereby air may mix with the vapor as it leaves the generator, and a skeleton frame supported over the burners.

2. In a burner as set forth, the combination with a tubular generator having a vaporizing chamber, of a gas chamber, a mixing chamber communicatively connecting the generator and the gas chamber, burners connected to the gas chamber, an air supply for the mixing chamber, extension burners comprising an extension generator and an extension gas chamber connecting the first generator and gas chamber, a brace for the extension burner, and a sectional skeleton frame supported by the main burner parts and the extension burner parts.

3. In a burner as set forth, a semi-circular tubular mixing chamber, a tubular gas chamber connected to one end of the mixing chamber, a brace connected to one end of the gas chamber and having a part spaced from and in parallelism with the gas chamber and being in turn connected to the tubular mixing chamber, a tubular generator interposed between the gas chamber and the parallel brace and adapted to deliver oil vapor into the mixing chamber, an air supply for the mixing chamber, a plurality of burners arranged in pairs connecting the parallel brace and the gas chamber and being in communication with the gas chamber.

and disposed under the generator for heating and vaporizing the oil, and means carried by the gas chamber for cutting off the mixture of gas and air from one pair of burners so that the mixture may enter the other pair of burners.

4. In a burner, a gas chamber, a tubular mixing chamber at one end, a brace at the other end having a return part in parallelism to and spaced from the gas chamber and being in turn connected to the casing of the mixing chamber, a generator tube intermediate the parallel brace and the gas chamber and communicating with and adapted to deliver oil vapor into the mixing chamber, an air supply for the mixing chamber, a plurality of retort fillers of gauze and absorbent material arranged in groups in said generator tube, burners arranged in pairs under the generator tube to deliver heat thereto, said burners being fixed to the brace and in turn communicatively connected to the gas chamber, and means carried by the gas chamber intermediate the communications of the burners with the gas chamber, so as to cut off the mixture of gas and air to one pair of burners.

5. In a burner as set forth, a tubular

generator, a mixing chamber at one end 30 thereof, an air supply therefor, a gas chamber connected to the mixing chamber and having burners under the tubular generator, an extension generator connected to the first generator, a tubular gas chamber connected to the first generator and having a 35 burner under the extension generator, means in the first gas chamber for cutting off the mixture of air and gas from one of the first burners, means carried by the extension 40 gas chamber for cutting off the mixture of air and gas from the extension gas chamber, whereby only the first mentioned burners may be used.

6. In a burner as set forth, a tubular generator, a tubular gas chamber parallel thereto, a tubular mixing chamber connecting the generator and the gas chamber, a frame supported above the gas chamber and generator, and an extension generator and an 50 extension gas chamber detachably connected to the first generator and gas chamber, and an extension frame detachably connected to the first frame.

In testimony whereof I hereunto affix my 55 signature.

JOHN W. FERREE.
